UNITED STATES PATENT OFFICE

ARTHUR P. HOLDEN, OF TORONTO, ONTARIO, CANADA

OIL-BURNER NOZZLE

Application filed September 21, 1927. Serial No. 221,085.

The principal objects of the invention are, to greatly simplify the construction of oil burner nozzles, and to eliminate the dripping of oil from the nozzle when the burner is not 5 in use.

A further object of the invention is to provide a simple and effective means of insulating the oil in passage to the discharge point of the nozzle against coking temperatures 10 and to preheat the air used in atomizing the oil.

The principal features of the invention consist in the novel construction of the burner element whereby the fuel oil is trapped in 15 a well below the level of the discharge and such oil is forced through a conduit by the combined pressure of the air on the surface of the oil within the trap and the inspirator suction effected by the flow of air around the 20 discharge end.

A further and important feature consists in the novel arrangement of air passages through the burner element between its outer walls and the oil carrying portion.

25 In the drawings, Figure 1 is a side elevational view of my improved burner with the side plate removed therefrom.

Figure 2 is a longitudinal mid-sectional view.

30 Figure 3 is a cross sectional view through the line 3-3 of Figure 1.

Figure 4 is a plan view of the burner on a reduced scale showing it attached to the blower element.

35 The present form of burner nozzle is constructed of a metal casting 1 which is formed with a central core passage 2 therethrough and laterally extending flanges 3 and 4 which form the side channels 5 and 6.

40 A fastening flange 7 is arranged at one end of the member 1 and is preferably set at an angle thereto so that the main burner casting will rest in a slightly downwardly sloping position when the flange 7 is in a vertical 45 position.

The forward end of the casting 1 is formed with a cylindrical boss 8 on the underside, the axis of which slopes at an acute backward angle from the axis of the main casting 1.

50 The boss 8 is internally threaded and has

secured therein a cup-shaped cap 9 which is provided with a shoulder 10 to abut the outer end of the boss and form a fluid tight joint.

A baffle wall 11 is arranged at the outward end of the central passage 2 and extends across the circular opening in the boss 8.

A recess 12 is formed at the outward side of the baffle 11 and communicates at its lower end with the opening through the boss 60 8 and the interior of the cap 9.

A boss 13 projects from the forward side of the recess 12 at its upper end and is surrounded on its upward and outward sides by a passage 14 and said recess is bored from its 65 inward side with a hole 15 which meets a hole 16 bored from the outward side.

A tube 17 is threaded into the hole 15 and extends downwardly into the interior of the cap 9 and a tube 18 is threaded into the hole 70 16 and extends outwardly from the boss 13 axially through a threaded opening 19.

The outer end 20 of the tube 18 is reduced to a desirable diameter for feeding oil and a nozzle 21 is threaded into the opening 19, said 75 nozzle having a tapering outlet surrounding the reduced end 20 of the pipe 18.

The outer sides of the passages 5 and 6 are covered by plates 22 and 23, the plate 23 having one or more openings 24 therein arranged 80 close to the flanged end 7.

An opening 25 extends through the flange 7 from the passage 5 and communicates with the intake of a suitable form of air pump 26, which is here shown of circular form. 85

The passage 6 communicates with the passage 5 at the outward end of the casting through an opening 27 which extends around the outer wall of the chamber 12 surrounding the oil tube 17. 90

The arrangement of the air chamber formed by the passages 6, 27 and 5 insulates the central passage 2 from direct contact with the heat of the combustion chamber into which the burner projects and the heat is absorbed by the flow of air which is drawn through the opening 24 into the passage 6 through the passage 27 to 5 and through the opening 25 to the pump. The pump discharges into the opening 2. 95 100

The oil to be distributed is introduced into the passage 2, preferably through the pump and is blown through said passage and strikes the baffle 11. The air flows under the baffle into the chamber 12 and passes through the passage 14 to the nozzle 21. The oil striking the baffle 11 is precipitated into the chamber formed by the hollow cap 9 and submerges the bottom end of the oil tube 17.

10 The pressure of the air within the cap 9 acting against the surface of the oil trapped in said cap, forces the oil up through the tube 17 and passages 15 and 16 to the nozzle tube 18 and the flow of air around the nozzle tube 18 out through the nozzle 21 accelerates the 15 movement of the oil and the air being directed through the tapering discharge nozzle atomizes the oil into a fine spray as it leaves the nozzle end 20 of the feed tube.

20 The operation of this nozzle is extremely simple and it produces a very desirable and efficient result in the atomization of the oil. The peculiar arrangement of the oil well in the cap 9 obviates the dripping of oil from the nozzle when the burner is not in use, as the column of oil within the tube 17 is longer than and extends below the discharge end of the tube 18 so that immediately upon the cessation of the flow of air through the nozzle 21 and the consequent relief of pressure within the cap 9 against the oil surface therein, the oil within the tube 17 flows back into the cap chamber siphoning the oil in the tube 18 back with it.

35 It will also be seen that the burner is very readily accessible for cleaning. The cap 9 may be very easily removed, as also may the nozzle 21 when the oil feed tubes may be easily and quickly removed if desired.

40 It will also be readily understood that with this type of burner, while the oil may be fed to the air pump and it is preferable to do so in order that the oil may form a lubrication for the pump, any atomizing taking place in the pump is not effective in carrying the atomized oil through to the burner, as the oil is precipitated by contact with the baffle 11 and by further baffling occurring in the chamber 12 and passage 14.

50 The oil feed is effected by the siphon produced by the flow of air through the nozzle and by the pressure of air against the oil precipitated in the chamber of the cap 9.

55 The nozzle is extremely simple in its construction and is therefore not costly to manufacture and it can be used in practically any type of furnace.

60 The definite circulation of a current of air from the passage in the burner is a very important factor in preventing the carbonization of the oil in the burner and in furnishing a supply of hot air to the nozzle.

What I claim as my invention is:

65 1. An oil burner nozzle having a passage therethrough, a baffle arranged intermediate

of the length of said passage, an oil trap connected with said passage below said baffle, a converging discharge nozzle arranged at the end of said passage, an oil tube having a discharge end arranged in said convergent passage and having its other end extending into the oil trap to a level below that of the discharge end. 70

2. An oil burner nozzle having a longitudinal passage therein, a baffle extending across said passage, an oil trap connected with said passage below said baffle, an air passage leading from the top of the oil trap, a convergent nozzle connected with said air passage and directing a flow of air downwardly, an oil tube extending upwardly through said air passage from said oil trap, and an oil discharge tube connected with the latter tube and directing oil through the discharge opening of said air nozzle above the lower end of the oil tube. 75

3. An oil burner nozzle, comprising a metal casting having a longitudinal passage through the centre thereof having a downwardly directed discharge opening, a hollow cap extending downwardly from said discharge opening and forming an oil trap, an air chamber extending upwardly in said casting from said oil trap, an air discharge nozzle leading downwardly from said air chamber, and an oil feed pipe leading upwardly from said trap and having a discharge into said air discharge nozzle. 80 90

4. An oil burner nozzle, comprising a metal casting having a longitudinal passage through the centre thereof having a downwardly directed discharge opening, a threaded boss surrounding said opening, a hollow cap threaded into said opening and forming an oil trap, an air chamber formed in said casting above said boss and having a downwardly directed discharge leading from its upper end, a threaded boss surrounding the discharge end of said air chamber, a convergent nozzle threaded in said threaded boss, and an oil feed tube leading upwardly from the oil trap in said cap and discharging downwardly through said threaded nozzle. 100 105 110

5. An oil burner nozzle, comprising a metal casting having a longitudinal central passage opening through one end, and a pair of side passages connected at the outer end of the casting and having an opening leading therefrom adjacent to the end opening of the central passage, means for drawing air through said side passages and discharging the same into the central passage, an oil trap arranged at the outward end of the central passage and extending downwardly therefrom, an air passage leading upwardly from the oil trap and having a downwardly directed discharge, and an oil feed tube leading upwardly from said oil trap and directing a flow of oil downwardly centrally of the air discharge passage. 115 120 125

6. An oil burner nozzle having a central passage therethrough for conducting oil and

air in intermingled relation, means in said passage for arresting the liquid oil content in its passage, an oil discharge connected with said arresting means, an air discharge, and 5 means for effecting a circulation of air around said central passage to maintain said passage at a temperature below the flashing temperature of oil.

7. An oil burner nozzle adapted to extend 10 into the combustion chamber of a furnace and having a passage therethrough extending from the inlet to the discharge end thereof and conducting a mixture of oil and compressed air, an oil trap arranged in said passage 15 in the path of flow of said oil and air mixture for arresting the liquid oil content of the mixture before it reaches the discharge end of said nozzle, an oil feed extending from said trap and conducting the arrested liquid 20 oil therefrom to the discharge end of the nozzle, and an atomizing nozzle arranged at the discharge end of said nozzle passage and being connected with the interior of said passage.
